(No Model.)

E. A. SPERRY.
ELECTRIC DRILLING MACHINE.

No. 405,187.

Patented June 11, 1891.

UNITED STATES PATENT OFFICE.

ELMER A. SPERRY, OF CHICAGO, ILLINOIS, ASSIGNOR TO THE SPERRY ELECTRIC MINING MACHINE COMPANY, OF SAME PLACE.

ELECTRIC DRILLING-MACHINE.

SPECIFICATION forming part of Letters Patent No. 405,187, dated June 11, 1889.

Application filed April 1, 1889. Serial No. 305,584. (No model.)

To all whom it may concern:

Be it known that I, ELMER A. SPERRY, a citizen of the United States, residing at Chicago, in the county of Cook and State of Illinois, have invented a new and useful Electric Drilling-Machine, of which the following is a specification.

My invention relates to automatic drilling-machines, particularly for mineral-drilling purposes, and has for its object to provide convenient means for drilling, and particularly for electrical drills or machines for drilling minerals and the like. This object I accomplish by means of the mechanism illustrated in the accompanying drawings, where-in—

Figure 1 is a cross-section through the body of the device. Fig. 2 is a rear view of a portion thereof with parts removed. Fig. 3 is a detail of the drill-rotating slot; and Fig. 4 is a cross-section on the line Z Z, showing the drill-rotating mechanism.

Like parts are indicated by the same letters in all the figures.

25 K is the field-magnet; K', the armature; K², a controlling balance-wheel on the shaft thereof; K³, the brushes; K⁴, arms on the frame to which the armature-shaft is journaled above; K⁵, the rear cross-piece of the 30 frame, through which the shaft K⁶ of the armature passes for a guide.

K⁷ is the base of the frame which supports the drill-driving mechanism, and in this frame is placed a foot-block K⁸, upon which rests 35 the lower end of the shaft K⁶. The shaft K⁶ carries two pinions L' L², which respectively mesh with the gears L³ and L⁴. These gears are journaled, respectively, in the upper portion of the frame L⁵ and the lower portion K⁷ 40 and are connected with the crank-plates M M in any desired and practical way, though preferably by a clutch mechanism such as that illustrated elsewhere in another case of even date herewith, Serial No. 305,585.

45 M' is a crank-pin having the collar M² thereabout and encircled by the straps M³, which are connected by the cross-bar M⁴, secured in place by the key M⁵ and passing through the slot M⁶ in the piece M⁷, which lies 50 between the two sides of the straps M³.

N is a transverse pin in the pitman-head N', and it is encircled by a collar N², and this collar by a strap N³, the ends of which are secured to the piece M⁷ by the transverse pin N⁴, all of which is more fully illustrated elsewhere in another application of even date herewith, Serial No. 305,585.

O is the forward part of the frame, cylindrical in cross-section and having the projecting cup-shaped end O', in which is secured and from which projects the cylinder O². In this cylinder is a reciprocating tube O⁴, having at its outer extremity the flange O⁵ and surrounded by a spring O⁶, which bears at one end against the inner end of the cup-shaped portion O' and at its other end against the flange O⁵.

O⁷ is the drill-rod, flanged and enlarged at O⁸ and provided with the clamp O⁹, to which is secured the drill-point O¹⁰. On the inner end of this drill-rod O¹¹, and rigid therewith, is the ratchet-wheel O¹², held in position by the spring-dog O¹³, pivoted on the pitman-head N'. This pitman-head is slotted at O¹⁴. Concentric with the ratchet-wheel is the arm O¹⁵, having the spring-dog O¹⁶, which engages such ratchet-wheel, and the projecting end O¹⁷, which passes into the slot O¹⁸ in the interior of the surface O.

All of the parts so far described are supported on the frame, which is provided with the side ledges P P, whereby the entire frame and all of the parts so far described are supported on the ribs P' P', which are supported on the side parts P² P² of the main supporting-frame. These said parts come together below in the supporting portion P³, through which passes the shaft P⁴, on which the entire machine is supported in any desired position and upon any suitable carriage. The cylinder O is slotted at R, and the head N' has a lip R' projecting through such slot. Projecting from the frame-pieces P² P² are the rods R² R², provided at their outer extremities with the cross-bar R³, in which is journaled the screw-rod R⁴, having the crank R⁵ at its outer end. This crank can be locked to prevent its rotation by the link R⁶. This screw-rod R⁴ passes through the lugs R⁷ R⁷, secured to the bottom of the 95 100

frame-plate K⁷, and between these lugs and screw-threaded on such rod is the screw-threaded ratchet-wheel R⁸.

R⁹ is a pivoted bell-crank lever, having at 5 one end the pawl R¹⁰ to engage such ratchet-wheel, and at the other the rod R¹¹, with the coupling R¹² and the end piece R¹³.

R¹⁴ is a standard on the frame, and R¹⁵ is 10 a spiral spring from such standard to the end R³ of the rod.

R¹⁶ is a latch on the lug R⁷, adapted to engage the end R¹⁷ of the pawl R¹⁰, and thus lock it slightly beyond the limit of its normal motion.

15 S S' are the conductors which supply the current to the motor.

S² is a switch, and S³ a cord leading from the handle thereof.

S⁴ is a pulley, over which such cord passes, 20 and S⁵ is a lug on the cross-bar R³, to which the cord S³ is connected.

S⁶ is the screw-pillar, on which the shaft P⁴ is secured, and by which the entire machine is supported.

25 R¹⁸ is a lock-pin for the nut R⁸.

The use and operation of my invention are as follows: The operation of the motor and the elastically-connected pitman and the driving mechanism therefor has been sufficiently 30 described elsewhere in another application of even date herewith, Serial No. 305,585, and is not specially claimed here. The operation of the motor rotates its shaft K⁶, and hence rotates the gears L³ and L⁴, and thus 35 moves the crank-pin M'. This retracts the pitman, which is elastically extensible, and which is connected at one end with the crank-pin M', and at the other with the pitman-head pin N. In this device the pitman-head is 40 cylindrical and reciprocates. As the machine is operated the pitman is retracted, carrying with it the pitman-head and all the connected parts and compressing the spring O⁶. When, 45 by the operation of the release and clutch mechanism which connects the gears L³ and L⁴ with the crank-plates M M, the drill and pitman-head are released, the spring O⁶ expands and forces the drill forward. As this 50 action takes place, the end O¹⁵ of the arm O¹³, projecting into the slot O¹⁶, causes such arm to be carried about its center as it moves longitudinally along the cylinder O, and its 55 spring-dog O¹⁴, engaging the ratchet-wheel O¹⁰ rigid on the drill-rod O¹⁷, causes the same to rotate, and thus the drill to be partly rotated before its next stroke is given. The head N' reciprocates but does not rotate within the cylinder O. The cylinder O is 60 fixed, and the drill-rod O¹⁷, with its drill at one end and its ratchet-wheel O¹⁰ at the other, rotates as the work progresses. Assuming that the latch R¹⁶ engages the end R¹⁷ of the dog R¹⁰, so as to throw the rod R¹¹ in its extreme forward position, where the end 65 R¹³ will never be engaged by the lip R' in the stroke, the screw-rod is free to be operated

by the crank R⁵, and when so operated, such screw-rod being fixed in its relation to the frame-pieces P² P², by reason of its being journaled so as not to reciprocate in the cross-bar 70 R³, which is supported by the rods R² R², will cause the entire upper portion of the frame which is supported on the ribs P' P' to reciprocate or move forward to the work when desired, the nut R⁸ being during this operation 75 locked by the pin R¹⁸. When it is not desired that this should be done by hand, as in the case of several machines being operated by a single workman, the crank is locked by a link R⁶, so as not to be capable of revolving. 80 In this case it is apparent that the rotation of the ratchet-wheel or nut R⁸ between the lugs R⁷ R⁷ will cause the upper frame carrying the operating mechanism to move forward along the ribs P' P'. Now, in order that this feed 85 may be automatically accomplished by the machine and that the feed may be proportional to the work, I employ the automatic feed mechanism consisting of the dog R¹⁰, elbow-crank lever R⁹, rod R¹¹, having the end 90 R³, which projects into the path of the lip R', and the retracting-spring R¹⁵. These parts are shown in the position at the end of the stroke, the crank locked and the rod having just been engaged so as to bring the operating 95 mechanism forward. As soon now as the head N' retreats the spiral spring R¹⁵ will retract the rod R¹¹ and end R¹³ and turn the elbow-crank lever on its pivot and bring the dog R¹⁰ into engagement with a lower tooth of 100 the ratchet-wheel R⁸. By the expansion of the spring and the operation of the machine the pitman-head N' rushes forward, the lip R' will engage the end R¹³, force it and the rod R¹¹ forward, raise the dog R¹⁰, and cause the 105 ratchet wheel or nut R⁸ to move on the screw-rod against the lug R⁷, and will thus move the operative parts forward to the work. If the blow is delivered to the work before the lip R' has engaged the projection R³, the mechanism will not feed until the drill by its operation has proceeded far enough into the work to cause the lip and projection to engage, when it will again feed, and hence the feeding is not only automatic, but nicely proportioned to the progress of the drill. When the operative parts have reached the limit of 110 their forward motion, further progress on their part will draw upon the cord O⁸, open the switch, and stop the machine. 115

If the velocities of the drill are traced from one dead-center to the other of the crank, it will be noticed that the velocity up to the center is gradually increasing, whereas from the middle of the stroke to the other dead-center it is gradually decreasing, which, taken in connection with the ratio and momentum of the interior rotating drill, will develop the additional fact that their friction is least in the center of the stroke, at which time the rotation should take place. The slot O¹⁶ has its curvature in the center and is straight at its 125 130

extremities. The cylindrical portion O, in which reciprocates the cross-head M', serves as an air-cushion for such cross-head.

The hand-feed may be used in conjunction with the automatic feed to increase the rapidity of operation of the machine, and both may be used together. The cam-groove O¹⁶ and arm O¹³, together with the pawls and ratchet connected with the drill-rod, co-operate together to rotate the drill, and hence are collectively called the "rotator." The feature of this rotator is its faculty of operating only in the middle of the retraction of the drill, that being the portion of the drill's excursion at which the friction of the parts is least. Of course other forms of rotators to accomplish the same result might easily be devised, and hence I do not wish to limit myself to the particular form of rotator used; but I use the term broadly.

The controlling-switch may obviously be of any desired kind, circuit connection, or location, the essential feature being that it shall be controlled in its application so as to affect the motor responsively to the variations in the relative positions of the fixed and movable frames incident to the excursion of the latter.

I claim—

30 1. In a drilling-machine, the combination of a reciprocating drill with a rotator operating upon said drill in the middle of its retraction only.

2. In a drilling-machine, the combination of a reciprocating drill and a driving-crank therefor, and a rotator for such drill operating only in the middle of the retraction of such drill.

3. In a mining-machine, the combination of a reciprocating drill, driving-crank therefor, and a rotator containing a pin and a cam, the latter so shaped as only to operate upon the drill in the middle of its retraction.

4. In a drilling-machine, the combination of a drill-rod with an inclosing-sleeve, a driving-spring about the same, and a guide-cylinder inclosing the whole with suitable end-bearing surfaces for said spring, so that the driving-spring is inclosed and supported internally and externally.

5. In a drilling-machine, the combination of a fixed frame with a frame movable thereon, a drill, an electric motor therefor supported on said movable frame, a switch to control such motor, said switch connected with such frames so as to affect the operation of the motor at any predetermined point in the excursion of the moving frame.

6. In a drilling-machine, the combination of

a fixed frame with a frame movable thereon, 60 a drill, an electric motor therefor on said movable frame, and a switch to control such motor, said switch secured on one frame and its handle connected with the other frame, so that it is operated to affect the motor responsive to the variations in the relative positions of the two frames.

7. In a drilling-machine, the combination of a fixed frame, a movable frame supported thereon and carrying the operative parts, a 70 screw-rod connecting the two frames, a crank thereon, a movable nut on such screw-rod, and a ratchet and dog, said dog connected with the drill, so that the movement of the latter causes the rotation of such nut to move the 75 operative part on such fixed frame.

8. In a drilling-machine, the combination of the fixed frame, a movable frame supported thereon and carrying the operative parts, a screw-rod connecting the two frames, a movable nut on said screw-rod, and a ratchet and dog, said dog connected with the drill, so that the movement of the latter causes the rotation of such nut to move the operative parts on the 80 fixed frame.

9. In a drilling-machine, the combination of a fixed frame, a movable frame supported thereon and carrying the operative parts, a screw-rod connecting the two frames, a crank thereon, a locking device for said crank, a 90 movable nut on such screw-rod, and a ratchet and dog, said dog connected with the drill, so that the movement of the latter causes the rotation of such nut to move the operative parts on the 95 fixed frame.

10. In a drilling-machine, the combination of a fixed frame, a movable frame supported thereon and carrying the operative parts, a screw-rod connecting the two frames and a crank thereon, a locking device for said crank, 100 a movable nut on said screw-rod, a locking device for said nut, and a ratchet and dog, said dog connected with the drill, so that the movement of the latter causes the rotation of such nut to move the operative parts on the 105 fixed frame.

11. In a drilling-machine, the combination of a fixed frame with a moving frame supported thereon and carrying the operative parts, a screw-rod connecting the same, a nut 110 and ratchet-wheel thereon, a dog to operate such ratchet-wheel, and a latch to hold such dog out of operative position.

Signed this 30th day of March, 1889.

ELMER A. SPERRY.
